UNITED STATES PATENT OFFICE

160,357

PLATE OR SIMILAR ARTICLE

Robert Y. Allen, Encino, Melvin Shaw, Beverly Hills, and Evan K. Shaw, Los Angeles, Calif., assignors to Metlox Manufacturing Company, Manhattan Beach, Calif., a corporation of California

Application May 10, 1949, Serial No. 2,562

Term of patent 14 years

(Cl. D44—15)

To all whom it may concern:

Be it known that we, Robert Y. Allen, residing at Encino, in the county of Los Angeles, State of California, Melvin Shaw, residing at Beverly Hills, in the county of Los Angeles, State of California, and Evan K. Shaw, residing at Los Angeles, in the county of Los Angeles, State of California, have invented a new, original, and ornamental Design for Plates or Similar Articles, of which the following is a specification, reference being had to the accompanying drawing, forming part thereof, in which:

The figure is a top plan view of a plate or similar article showing our new design. The dominant feature thereof resides in the ornamentation drawn in full lines as shown.

We claim:

The ornamental design for a plate or similar article, as shown and described.

ROBERT Y. ALLEN.
MELVIN SHAW.
EVAN K. SHAW.
